R. M. Brooks.

Cotton Planter

No 28,829.

Patented Jun. 26, 1860.

UNITED STATES PATENT OFFICE.

R. M. BROOKS, OF GREENVILLE, GEORGIA.

IMPROVEMENT IN CULTIVATORS.

Specification forming part of Letters Patent No. 28,829, dated June 26, 1860.

To all whom it may concern:

Be it known that I, R. M. BROOKS, of Greenville, Meriwether county, Georgia, have invented certain new and useful Improvements in Seed and Guano Distributing Cultivators; and I do hereby declare that the following is a full, clear, and exact description of the same, reference being had to the accompanying drawings, and to the letters of reference marked thereon.

The nature of my invention consists in constructing and arranging the several parts of this machine substantially in the manner hereinafter described.

In the annexed drawings, Figure 1 represents a side elevation. Fig. 2 is a plan view of the machine. Fig. 3 is a vertical section of the seed-box. Fig. 4 is a perspective of the seed-box. Fig. 5 is a view of the guano-slide.

In the figures, A represents the beam of the plow, which is made in any convenient and strong manner. B represents the standard at the rear of the beam, which is secured to said beam in the usual manner. To the lower end of the standard is secured the usual bull-tongue for opening a furrow for the reception of grain.

N represents a frame, which is secured to the side of the beam, and which is for the purpose of sustaining one side of the axle of a wheel, D, which supports the front of the beam. The axle of the said wheel D has one bearing in a journal-box secured to the under side of the beam, while its other bearing is in a journal-box secured to the under side of the frame N, as represented in Fig. 1. The periphery of the wheel D is corrugated or scalloped, as seen in Fig. 1. Secured to the wheel D is a pulley, E, around which passes a band for the purpose of driving the seed-cylinder.

H represents a seed-box, which is secured to the back of the standard B by means of a bolt, or otherwise, as seen in Fig. 1. The seed-box H is not made in the usual shape, but is made smaller at the top than it is at the bottom. The reason of this is that in seeding cotton or distributing guano they are both liable to pack in the box, catching upon the inclined sides of the common V-shaped box. When the box is larger at bottom, as in this case, the cotton-seed and guano will fall toward the dis-

tributing-cylinder more readily and can never pack or clog.

In the bottom of the seed-box a distributing-cylinder, G, is secured. This cylinder revolves upon an axis which has its bearings in the sides of the box. Upon the periphery of the cylinder are teeth or pins *x x x*, which cut through an opening in the side of the box and carry out the cotton-seed from the box.

P represents the spout attached to the seed-box, through which the seed, &c., falls as it passes to the ground.

I represents a slide, which is provided with a slot or narrow opening, *s*. This slide is so arranged as to slide in the spout P and cover the opening in the side of the box, through which the cotton-seed is carried out. The object of using this slide provided with the narrow opening is for distributing guano. The teeth upon the cylinder G cut through the slot in the slide I and carry out the guano, which falls to the ground through the spout P.

F represents a pulley secured to the axis of the cylinder G. The band M passes around this pulley F and around the pulley E, and serves to communicate motion from the wheel D to said seed-cylinder G.

L represents a tightening-pulley, which is attached to an arm which depends from the frame N. This arm is adjustable by means of a bolt and nut, (the bolt working in a slot in the frame N,) so that the pulley may be moved so as to tighten or slacken the band.

K represents a curved metallic bar, which is secured in two points to the plow, being secured to the beam and to the standard, as is shown in Fig. 1. There are two of these bars, one on each side of the standard. The standard is provided with several holes, as seen at *a*, so that by removing the bolt which secures the bar to the standard said bar may be adjusted to or from the ground. The ends of these bars are formed for covering the grain as it falls before them from the hopper. Different-shaped blades may be attached to them for cultivating, if necessary.

By using a cylinder in the bottom of the seed-box H, which is provided with seed openings upon its periphery, corn or other grain may be distributed; or another box provided

with a proper cylinder may be substituted and used for the purpose of seeding corn or other grain.

Having thus fully described my invention, what I claim as new, and desire to secure by Letters Patent, is—

The arrangement of the seed-box H, as constructed, with the standard B, distributing-

cylinder G, provided with pins or teeth x x, and with the slide I, provided with an opening, s, when the same are used, substantially as and for the purpose specified.

R. M. BROOKS.
